(No Model.)

D. SCHMITT.

HEARSE.

No. 269,122.

Patented Dec. 12, 1882.

UNITED STATES PATENT OFFICE.

DANIEL SCHMITT, OF NEWARK, NEW JERSEY.

HEARSE.

SPECIFICATION forming part of Letters Patent No. 269,122, dated December 12, 1882.

Application filed June 15, 1882. (No model.)

To all whom it may concern:

Be it known that I, DANIEL SCHMITT, a citizen of the United States, residing at Newark, in the county of Essex and State of New Jersey, have invented certain new and useful Improvements in Hearses; and I do hereby declare the following to be a full, clear, and exact description of the invention, such as will enable others skilled in the art to which it applies to make and use the same, reference being had to the accompanying drawings, and to letters of reference marked thereon, which form a part of this specification.

This invention relates to certain improvements by means of which a hearse may be increased or diminished in capacity, so as to receive either a small or large sized coffin, at pleasure, thereby avoiding the necessity of an undertaker having more than one or an extra large or small hearse for special purposes.

My improvements will be hereinafter fully described and shown, and finally pointed out in the claims.

In the drawings, in which similar letters of reference indicate corresponding parts in each of the several figures, Figures 1 and 2 are elevations of the front portion of a hearse illustrating two forms of my invention. Figs. 3 and 4 are detail sectional views of the same, taken through lines *x* and *y*, respectively.

Heretofore it has been necessary for undertakers or liverymen, as a rule, to keep three different-sized hearses, in order to appropriately meet the demands for small persons or children, ordinary-sized persons, and those of extraordinarily large size.

In carrying out my invention I provide a hearse, preferably in front, with an adjustable extension adapted to slide or open in and out, so that the length of the hearse may be increased or diminished some eighteen inches, more or less, at pleasure. This extension is constructed and arranged in one case as follows: A frame, *a*, Figs. 1 and 2, provided with a glass or panel, *b*, Fig. 4, as may be preferred, is secured to a top or slide, *B*, which, together with the frame, is arranged to slide in and out horizontally between the roof and its inside lining in suitable grooves arranged therein for the purpose. On the inside of said

frame *a*, at the outside edges, are hinged two glassed or paneled frames, *c*, which, when the extension is in use, open outward and fasten by means of suitable catches to the sides of the hearse, completely filling up the side space 55 and extending the length of the interior chamber of the hearse, as indicated in Fig. 1. When the extension is not in use the frames or panels turn inward or back, and fasten against the frame *a* by appropriate hooks or other 60 fastenings, as indicated.

Suitable rollers, *f*, are provided to facilitate the operation of moving the extension in and out when required. Suitable dowels, *g*, at the bottom of the frame engage with corresponding apertures in the back end of the boot, when the device is in use, to assist in holding it in position.

In Fig. 2 the extension sides are shown hinged instead of sliding in and out, in which case the top *B*, instead of sliding under the roof, is hinged at the top of the boot *D*, and when in use opens upward and engages with the front end of the hearse, as indicated. The glassed or paneled frames *C* are hinged to the front end of the hearse, as shown in Fig. 3, at each side instead of to the frame, as above described, and when extended open outwardly and fasten against the side of the boot *D*, or to the top *B*, and when not extended close and 80 fill up the front, as will be readily understood by examining the figure last referred to. In this case the frame *a* is dispensed with. It is manifest, however, that the top may be hinged to the end of the body and the frames to the 85 sides of the boot, if preferred. Thus the extension is inclosed on all the exposed sides.

Having thus described my invention, what I claim, and wish to have secured by Letters Patent, is—

1. A hearse provided with an adjustable extension, whereby the body may be lengthened or shortened to receive a long or short coffin, as set forth.
2. A hearse provided with an adjustable extension inclosed upon all the exposed sides, as and for the purpose set forth.
3. In a hearse, the combination, with the body thereof, of an adjustable frame or frames adapted to fit into and inclose the end, and to 100

be moved in and out to increase and diminish the length of the body, as and for the purpose set forth.

4. In a hearse, the combination, with the body thereof, of a frame, as *a*, top or slide, as *B*, and frames, as *c*, arranged and operating substantially as and for the purpose set forth.

5. In a hearse, the combination, with the body thereof, of the adjustable top *B* and

frames *C*, arranged and operating substantially as and for the purposes set forth.

In testimony that I claim the foregoing I have hereunto set my hand this 25th day of May, 1882.

DANIEL SCHMITT.
